ENDLESS-TRACK GUN-CARRIAGE.

1,371,054.

Specification of Letters Patent.

Patented Mar. 8, 1921.

Application filed November 22, 1919. Serial No. 339,904.

To all whom it may concern:

Be it known that I, EMILE RIMAILHO, a citizen of the French Republic, and residing in Paris, France, 12 Rue de la Rochefoucauld, have invented certain new and useful Improvements in and Relating to Endless-Track Gun-Carriages, of which the following is a complete specification.

The invention relates to endless track gun carriages and has for its object a constructional form in which the apparatus for traversing the gun by hand is intimately connected with the service of the gun by the fact that the hand wheel for effecting the traversing of the gun is placed on the gun carriage near the sighting and elevating devices, to be worked by the same gun layer as these latter to simplify the operation of pointing the weapon.

The accompanying drawing which represents this constructional form in side elevation shows an endless track gun carriage in the firing position having a platform on which is carried the trunnions supporting the gun 2 and recoil mechanism; 3 is the elevating hand wheel, 4 is the traversing hand wheel working by means of bevel pinions 5 and 6 and suitable return mechanism 7 and 8, a train of toothed reducing wheels 9 which drive the toothed wheel 10 rigidly connected to the driving sprocket of the endless track 11. It should be noted that this train of reducing wheels is thrown into gear by the pinion 12 with the toothed wheel 10 only when the gun carriage is in the firing position, by the aid of any kind of clutch 13, such as a sleeve or a dog clutch for example. As can be seen from the drawing the gun layer has in front of him the sighting apparatus, and within reach the elevat-

ing and traversing hand wheels. It follows that when the gun layer actuates his traversing hand wheel he causes one endless track to move which brings about the rotation of the endless track gun carriage upon the ground in the direction which he deems suitable.

The traversing transmission devices described (bevel and other pinions) may be replaced by other parts such as endless screws, helicoidal wheels, chains with chain pinions for example and the transmission shafts may be rigid or not. The apparatus may exist for only one of the endless tracks or be doubled by a second device working the other endless track.

What I claim is:

In an endless track gun carriage, a frame, endless tracks supporting the frame, a gun mounted on the frame, means for elevating the gun, a gear wheel on one of the sprockets of the tracks, gearing for operating the gear wheel of the sprocket wheel, means for throwing the gearing into and out of engagement with the gear wheel of the sprocket, and means for operating the said gearing, said means consisting of a vertical shaft arranged below the gun elevating means with its upper end adjacent thereto, a hand wheel geared with the upper end of the shaft, and a horizontal shaft having one end geared with the lower end of the vertical shaft and its other end with the said gearing.

In testimony whereof I have hereunto set my hand at Paris, France, this 24th day of October, 1919.

EMILE RIMAILHO.

In the presence of—
CHAS. P. PRESSLY.
